United States Patent Office

Des. 220,615
Patented May 4, 1971

220,615

PORABLE OUTHOUSE

William L. Thompson, Pueblo Mountain Park,
Beulah, Colo. 81023

Filed Mar. 3, 1970, Ser. No. 21,709

Term of patent 14 years

Int. Cl. D25—04

U.S. Cl. D13—1

Fig. 1

Fig. 2

Fig. 3

Fig. 4

Fig. 5

Fig. 6

FIG. 1 is a plan view of the design for a portable outhouse.

FIG. 2 is a front elevational view thereof.

FIG. 3 is a side elevational view thereof.

FIG. 4 is a rear elevational view thereof.

FIG. 5 is a sectional plan view as taken from the indicated line 5—5 at FIG. 3.

FIG. 6 is a fragmentary sectional detail of an edge member of the design to better illustrate the construction thereof.

I claim:

The ornamental design for a portable outhouse, as shown.
